DISPLAY BOX

Samuel Braun, Rye, N.Y., assignor to B.C.N. Design Products, Inc., Amityville, N.Y., a corporation of New York

Filed Mar. 31, 1965, Ser. No. 84,539

Term of patent 14 years

(Cl. D58—12.7)

FIG. 1.

FIG. 2.

FIG. 3.

FIG. 4.

FIG. 5.

FIG. 7.

FIG. 8.

FIG. 6.

FIG. 1 is a top plan view of a display box embodying my new design, the box being shown in closed condition; FIG. 2 is a front elevational view thereof; FIG. 3 is a side elevational view thereof; FIG. 4 is a rear elevational view thereof; FIG. 5 is a bottom plan view thereof;

FIG. 6 is a three-quarter perspective view, showing the display box in open condition exposing the article-carrying support therein;

FIG. 7 is an end elevational view of the article-carrying support taken from the left hand end thereof as viewed in FIG. 6; and

FIG. 8 is a bottom plan view of the article-carrying support.

I claim:

The ornamental design for a display box, as shown.
